UNITED STATES PATENT OFFICE

2,561,981

CAM GRINDING APPARATUS

Clarence J. Green, Worcester, Mass., assignor to
 Norton Company, Worcester, Mass., a corporation of Massachusetts

Application December 17, 1948, Serial No. 65,921

8 Claims. (Cl. 51—101)

1

The invention relates to grinding machines and more particularly to a cam grinding machine.

One object of the invention is to provide a simple and thoroughly practical cam grinding machine for grinding predetermined contours on a work piece. Another object is to provide a cam grinding apparatus for grinding a contour of a predetermined length on the periphery of a work piece. Another object is to provide a cam grinding apparatus for grinding a contour of a predetermined length around the periphery of a roll, regardless of the diameter of the roll, from the same master cam. Another object is to provide a cam grinding apparatus with an adjustable speed-up device for speeding up rotation of the work piece being ground relative to rotation of the master cam. Another object is to provide a cam grinding apparatus having a single master cam with a direct proportional device to speed up the rotation of the roll being ground relative to the rotation of the master cam so that the original shape can be extended around the periphery of the roll as it is reduced in size by regrinding operations so as to produce the same shape in blanks being rolled.

Another object of the invention is to provide a cam grinding apparatus for grinding a predetermined shape in the periphery of a roll used in a rolling operation. Another object is to provide an apparatus for grinding the periphery of rolls with an adjustable work rotation speed-up mechanism for speeding up rotation of the roll being ground relative to the master cam whereby a single master cam serves to grind a form of the same peripheral length regardless of the diameter of the roll being ground. A further object is to provide a cam grinding apparatus for grinding a form of a predetermined length on the periphery of a roll being ground by means of a single master cam as the roll is reduced in diameter due to successive regrinding operations so that uniformly shaped blanks may be rolled thereby.

In the accompanying drawings, in which is shown one of various possible embodiments of the mechanical features of this invention,

Fig. 1 is a fragmentary plan view of the improved cam grinding apparatus having parts broken away and shown in section to show part of the work driving mechanism;

Fig. 2 is a fragmentary front elevation of the work driving mechanism showing the two-speed clutch, taken approximately on the line 2—2 of Fig. 1;

Fig. 3 is a right hand end elevation, taken ap-

2

proximately on the line 3—3 of Fig. 1, showing a portion of the work driving mechanism;

Fig. 4 is a fragmentary cross section, on an enlarged scale, taken approximately on the line 5 4—4 of Fig. 1, through the rock bar showing a right hand elevation of the work speed-up and slow-down mechanism;

Fig. 5 is a fragmentary vertical sectional view, taken approximately on the line 5—5 of Fig. 4; 10 Fig. 6 is a fragmentary vertical sectional view, taken approximately on the line 5—5 of Fig. 4, showing the work speed-up mechanism in elevation;

Fig. 7 is a fragmentary cross sectional view, 15 taken approximately on the line 4—4 of Fig. 1, similar to Fig. 4 but showing the parts in another position;

Fig. 8 is a diagrammatic view of a metal rolling apparatus in which the lower roll is ground on 20 the improved cam grinding machine;

Fig. 9 is a view of the lower roll showing the extended formed surface on the roll when the roll has been reground to a smaller diameter;

Fig. 10 is a side elevation of an article rolled 25 by the apparatus shown in Fig. 8; and

Fig. 11 is a front elevation of the grinding machine.

A cam grinding apparatus has been illustrated in the drawings comprising a base 9 which supports a longitudinally movable table 10 on the usual V and flat way (not shown) on the base of the machine. A transversely movable rotatable grinding wheel 11 is provided which is mounted in a conventional manner on a transversely movable wheel slide 30 so that the wheel 30 may be moved toward and from the work table 10 to grind a work piece to the required and predetermined size. A manually operable feed wheel 31 is mounted on the front of the machine base 40 and is operatively connected to rotate a feed screw (not shown) to cause the grinding wheel 11 and the wheel slide 30 to move transversely toward and from the work table 10, depending upon the direction of rotation of the feed wheel 31.

This mechanism is substantially identical with that disclosed in the prior U. S. patent to C. H. Norton No. 762,838 dated June 14, 1904, to which reference may be had for details of disclosure not contained herein. The feed wheel 31 may be actuated either manually or automatically as desired. A mechanically actuated feed pawl 32, such as shown in the prior patent above referred to, is reciprocated automatically to advance the grinding wheel 11 at the ends of the

55 reciprocatory stroke of the work table 10.

The work table 10 may be reciprocated longitudinally relative to the base 9 by means of a manually operable traverse mechanism comprising a traverse wheel 200 rotatably mounted on the front of the machine base. The traverse wheel 200 is connected to rotate a gear 201 which meshes with a gear 202 mounted on a rotatable shaft 203. The shaft 203 also supports a gear 204 which meshes with a rack bar 205 depending from the underside of the work table 10. It will be readily apparent from the foregoing disclosure that a manual rotation of the traverse wheel 200 will be imparted through the rack and gear mechanism above described to produce a longitudinal traversing movement of the table 10. The direction of rotation of the traverse wheel 200 serves to determine the direction of movement of the table 10.

The table 10, if desired, may be reciprocated longitudinally by a power operated mechanism such as shown in the prior patent above referred to. This mechanism may comprise a rotatable power driven shaft 206 which is driven by means of a multiple speed drive contained with a casing 207. The rotatable shaft 206 is connected through a reversing clutch (not shown) which is actuated by means of a reversing lever 208. The reversing lever 208 is actuated by adjustable table dogs 209 and 210 which are adjustably mounted in a T-slot 211 formed in the front edge of the table 10. This table traverse mechanism above described is substantially identical to that shown in the above mentioned prior patent, to which reference may be had for details of disclosure not contained herein. The table 10 serves as a support for a rock bar 12. The rock bar 12 is provided with trunnions 13 and 14 at its opposite ends (Fig. 1) which are rotatably journaled in brackets 15 and 16. The brackets 15 and 16 are fixedly mounted on the upper surface of the table 10.

The rock bar 12 serves as a support for a headstock 17 and a footstock 18 which are provided with work supporting centers 19 and 20 respectively. The headstock 17 is provided with a rotatably mounted master cam spindle 21 which is supported in bearings 22 and 23. A master cam 24 is mounted on the master cam spindle 21. A frame 25 is fixedly mounted on the table 10 and serves as a support for a rotatably mounted master cam roller 26. The master cam roller 26 is keyed on a rotatable shaft 27 which is journaled in brackets 28 and 29 which are formed integral with the frame 25.

A casing 35 is fixedly mounted on the table 10 and serves as a support for a work driving motor 36. The work driving motor 36 is provided with a motor shaft 37 which is connected to rotate a worm 38. The worm 38 meshes with a worm gear 39 which is keyed on a rotatable shaft 40. The shaft 40 is journaled in antifriction bearings 41 and 42 which are supported within the casing 35.

A two-speed drive is provided between the shaft 40 and the master cam spindle 21 to facilitate changing the speed of rotation of the master cam spindle 21 and the work piece being ground. This mechanism may comprise a pair of gears 45 and 46 which are keyed on opposite ends of the shaft 40. The gears 45 and 46 mesh with gears 47 and 48 respectively which are keyed on rotatable clutch members 49 and 50 respectively. The clutch members 49 and 50 are rotatably supported on a shaft 51 which is journaled for rotation within bearing surfaces formed within the

clutch members 49 and 50. A slidably mounted clutch member 52 (Fig. 2) is slidably keyed on the shaft 51. A manually operable clutch shifting lever 53 is fixedly supported on a rock shaft 54. The rock shaft 54 also supports a yoked member (not shown) which engages a groove (not shown) on the clutch member 52. It will be readily apparent from the foregoing disclosure that by manual shifting of the lever 53, the clutch member 52 may be engaged either with the clutch member 49 or the clutch member 50 to impart a rotary motion to the shaft 51.

A multiple V-groove pulley 55 is keyed on the left hand end of the shaft 51. The pulley 55 is connected by multiple V-belts (not shown) with a multiple V-groove pulley 56 which is supported by an anti-friction bearing 57. A universal joint 58 is drivingly connected with the pulley 56. The universal joint 58 is fixedly connected to one end of a shaft 59. A universal joint 60 connects the right hand end of the shaft 59 with the master cam spindle 21. It will be readily apparent from the foregoing disclosure that by providing the universal joints 58 and 60, a substantially uniform rotation may be imparted to the master cam spindle 21 and the work piece being ground during oscillating movement of the rock bar 12.

In the rolling of shaped metallic blanks such as is used in the silver-ware and cutlery trade, it is desirable to provide a roll for the rolling operation having a predetermined form on its periphery so that a work blank being rolled will be produced having the desired longitudinal shape. In order to produce a predetermined shape in the periphery of the roll used in the rolling operation from a single master cam, it is desirable to provide a suitable speed-up mechanism between the master cam spindle and the work piece being driven thereby to facilitate an acceleration of the work speed relative to the speed of rotation of the master cam 24 so that as the roll being ground is reduced in diameter by successive regrinding operations, a form of a predetermined length may be produced on the peripheral surface of the roll. This mechanism enables rolling work pieces to the same longitudinal shape regardless of the diameter of the roll being ground without the necessity of providing a plurality of master cams. The speed-up mechanism as illustrated in the drawings is mounted on the right hand end of the master cam spindle 21.

The master cam spindle 21 is provided with an integral flange 65 (Figs. 5 and 6) and a cylindrical portion 66. The cylindrical portion 66 of the master cam spindle 21 serves as a support for an annular member 67. A spacing collar 68 is interposed between the annular member 67 and the flange 65. A plurality of clamping screws 69 (only one of which is shown in Fig. 5) are provided for locking the annular member 67 and the spacing collar 68 to the flange 65 so that the annular member 67 is rotated with the master cam spindle 21. A bracket 70 is mounted on the periphery of the annular member 67. A pair of clamping screws 71 and 72 pass through the bracket 70 and have their heads engaging an arcuate T-slot 73 formed in the periphery of the annular member 67. It will be readily apparent from the foregoing disclosure that by loosening the screws 71 and 72, the bracket 70 may be adjusted about the periphery of the member 67 as desired. The bracket 70 serves as a support for an arcuate member 74 which is pivotally connected by means of a stud 75 with the bracket 70. The right hand end of the arcuate member (Fig.

4) is provided with a roller 76 which is supported by a stud 71 carried by the arcuate member 74. The roller 76 is arranged to engage the internal cam 78 formed on the inner periphery of an annular ring 79. The ring 79 is provided with a pair of downwardly extending lugs 80 and 81 which are fastened to the rock bar 12 by means of cap screws 82 and 83 so that the annular ring 79 is rigidly positioned on the rock bar 12.

A slide 85 is supported by a radially extending slot 86 formed in the annular member 67. The slide 85 carries a stud 87 which rides in an elongated arcuate slot 88 formed in the arcuate member 74. A pair of plates 89 and 90 are fixedly mounted on the peripheral surface of the annular member 67 to prevent the slide 85 from moving outwardly beyond the maximum position as illustrated in Fig. 4.

A driving head 94 is rotatably mounted on the cylindrical portion 66 of the master cam spindle 21 and is held in position thereon by means of a collar 95. The driving head 94 is provided with an angularly positioned slot 96 which is preferably arranged at approximately 45° relative to a radial plane passing through the axis of the master cam spindle. The slide 85 is provided with a stud 98 which supports a roller 97. The roller 97 rides in the slot 96. It will be readily apparent from the foregoing disclosure that when the slide 85 is moved downwardly (Fig. 4) in a radial direction relative to the annular member 67, the roller 97 carried thereby riding in the angular slot 96 will impart an accelerating motion to the driving head 94 so that the head 94 moves at a faster rate than the rotation of the annular member 67.

A tension spring 99 is provided for exerting a pull on the driving head 94 in a clockwise direction relative to the annular member 67. The left hand end of the spring is fastened to a stud 100 carried by the annular member 67. The right hand end of the spring is fastened to a stud 101 carried by the driving head 94. An adjustably mounted stop screw 105 is supported by a lug 106 on the annular member 67. A lock nut 107 serves to lock the screw 105 in adjusted position. It will be readily apparent from the foregoing disclosure that the tension of the spring 99 will serve normally to maintain a stop surface 108 on the driving head 94 in engagement with the stop screw 105.

A driving block 110 is adjustably supported by means of a clamping bolt 111 on the driving head 94. The head of the clamping bolt 111 rides in an arcuate T-slot formed in the front face of the driving head 94.

A driving dog (not shown) is mounted on the neck 113 of the roll 114 to be ground. The driving dog is arranged to engage an aperture 116 in the face of the driving block 110.

The cam grinding apparatus disclosed is particularly intended for grinding a peripherally extending form on a roll utilized for a rolling operation for rolling metallic blanks such as spoon blanks for manufacturing silver spoons and the like in which a blank must be formed of varying thickness and shape from length to length. To illustrate, a rolling apparatus has been illustrated in Fig. 8 comprising the shape droll 114 which is located in a vertical plane with a cylindrical roll 115. A metal blank 116 to be rolled is provided at its right hand end with an enlarged end portion 118 which is arranged to be engaged by a longitudinally extending groove 117 formed in the

periphery of the roll 114. The roll 114 is provided with a predetermined shaped portion represented by the arc A—B—C which when rotated in a clockwise direction will roll the blank 116 to produce a shaped blank 120 (Fig. 10).

As one example, the roll 114 is preferably 5½" in diameter and the finished blank to be rolled is approximately 9" in length which means that the form produced on the roll 114 represented by the arc A—B—C equals approximately 187.5°. The master cam 24 is preferably designed so that it will generate the predetermined shape on a 5½" diameter roll. When the roll 114 becomes worn during usage it is necessary to regrind the periphery thereof to provide the desired shape and finish for the rolling operation. As the roll 114 is reduced in diameter due to successive regrinding operations, it is necessary to extend the formed surface represented by the arc A—B—C so that a 9" blank may be rolled thereby. For example when the roll 114 becomes worn due to usage and successive regrinding operations from 5½" in diameter to 5" in diameter, it will be necessary to increase the formed surface thereon as represented by the arc A—B—C to approximately 206.3° in order to produce a formed blank 9" in length (Fig. 9).

After the groove 117 becomes ground away, it may be necessary in a separate grinding operation to regrind the longitudinal groove 117 so that it will grip the end 118 of the blank 116 to be ground.

During the initial grinding operation on a 5½" diameter roll, the stop screw 105 is adjusted to turn the driving head 94 in a counterclockwise direction relative to the annular member 67 so that the angular slot 96 causes a downward movement of the roller 97 (Fig. 4) to move the slide 85 also in a downward direction so as to rock the member 74 in a clockwise direction to position the roller 76 so that it will not engage the cam face 78 during its rotary motion. The initial roll having the groove 117 previously formed therein may be ground in the usual manner by feeding the grinding wheel 11 transversely into the surface of the roll 114 while the master cam spindle 21 is rotated. The rock bar 12 is oscillated in a controlled movement by means of the master cam 24 to generate the predetermined contour on the roll 114. This operation in case of a 9" blank as illustrated will produce a form A—B—C. The remaining surface of the roller as represented by the arc A—D—C being formed as a true cylindrical surface. The roll 114 thus produced is mounted in the rolling machine and work pieces are inserted as the roll revolves so that the thickened end portion 118 is engaged by the groove 117 which serves to pull the blank through the machine and due to the shape generated on the surface as represented by the arc A—B—C, to generate a formed blank 120 as illustrated in Fig. 10.

When the initial roll becomes worn and requires regrinding, the regrinding reduces the diameter of the roll and it is necessary to extend the formed surface A—B—C through a greater angle in order to produce a blank of the same length and shape. This is accomplished by rotating the master cam spindle 21 so that the roller 76 coincides with the 187.5° position on the graduated scale formed on the side face of the ring 79. With the roller 76 in this position, the screw 105 is adjusted so that the tension of the spring 99 will shift the driving head 94 in a clockwise direction relative to the annular mem-

ber 67 so as to allow the slide 85 to move upwardly (Fig. 4) a sufficient distance so that the member 74 is rocked in a counterclockwise direction until the roller 76 engages the surface of the cam 78. On the next regrinding operation it will be necessary to lengthen the arc of grinding A—B—C and to accomplish this, the bracket 70 may be shifted around the periphery of the annular member 67 by loosening the clamping bolts 71 and 72 so that when the master cam spindle 21 is rotated, the roller 76 riding on the gradually rising surface of the cam 78 from the 187.5° position to zero will transmit an accelerated motion to the driving head 94 to gain the additional arc required so that the peripheral length of the surface represented by the arc A—B—C (Fig. 8) will remain constant. In actual practice the member 74 may be calibrated with a graduated scale so that if a two degree gain is required, the bracket 70 may be precisely positioned by consulting a calibrated table to give the desired results.

After the bracket 70 has been adjusted to its new position, the grinding operation may then be started. As the roller 76 rides around the surface of the cam 78 in a counterclockwise direction, the rise of the cam 78 acting through the roller 76 serves to rock the member 74 about its pivot stud 75 in a clockwise direction to cause a downward movement of the slide 85. The downward movement of the slide 85 serves through the roller 97 riding in the angularly positioned slot 96 to accelerate the rotary motion transmitted to the driving head 94. It will be readily apparent from the foregoing disclosure that by adjustment of the bracket 70 relative to the annular member 67, the desired amount of gain may be had in the acceleration of the driving head 94 to produce the desired surface on the roll 114.

This adjustment is required on successive regrinding operations so that for example when the roll has been worn by use and regrinding to 5" in diameter, it will require approximately 206.3° of arc A—B—C (Fig. 9) to produce the desired length and contour on the finished blank 120. When the roll becomes worn to the 5" diameter the roller 176 engages the cam 78 at the 187.5° position and during its rotation from this position to zero, the roller 76 through the rocking of the member 74 causes a downward movement of the slide 85 to move the roller 97 downwardly in the angularly positioned slot 96 so that the driving head 94 is accelerated to move through 206.3° thereby producing a surface on the roll as represented in Fig. 9 that will produce a rolled blank 120 of the same length and contour. It will be readily apparent from the foregoing disclosure that by setting up the roller 76 for the initial angular rotation required and then by adjusting the position of the bracket 70 to vary the angular acceleration of the driving head 94 any desired movement may be obtained to equalize and offset reductions in diameter of the roll being ground.

As illustrated in the drawings, the cam face 78 has been graduated to 240° which is sufficient for certain classes of rolls to be ground. The remaining ungraduated portion is a substantially cylindrical clearance face joined with a blending curve which blends with the cam shape at the zero point. If desired the cam face 78 may be extended through a greater arc if the nature of the work to be ground requires.

The operation of this improved grinding ap-

paratus will be readily apparent from the foregoing disclosure. Assuming adjustments have been previously made so that the roller 76 remains out of contact with the cam 78, the initial full diameter roller 114 may be ground by the usual cam grinding operation, that is, by rotation of the master cam spindle which transmits the motion of the master cam 24 to cause a predetermined rocking movement of the rock bar 12 to generate the predetermined shape as represented by the arc A—B—C (Fig. 8) on the roll 114. After the roll becomes worn and it becomes necessary to regrind the surface thereof the mechanism is adjusted in a manner above described that is in the present case rotating the master cam spindle 21 until the roller 76 is opposite the 187.5° position after which the stop screw 105 is adjusted into engagement with the stop surface 108. The bracket 70 is then adjusted to shift the arcuate member 74 so as to vary the lever arms between the axis of the stud 75, the axis of the stud 87 and the axis of the stud 77 so that during the rotation of the master camshaft 21 and the annular member 67 through 187.5°, the driving head 94 will be accelerated the desired amount so that the form generated on the roller 114 as represented by the arc A—B—C will be equal in length to the initial arc. On each successive regrinding operation it will be necessary to make adjustment of the position of the bracket 70 to compensate for reduction in diameter of the roller being reground to insure generating a form of the predetermined peripheral length.

As disclosed above, the mechanism has been described as set up for producing a formed blank 120 which is 9" in length. If it is desired to produce blanks of a different length, the mechanism is set up accordingly to generate the desired arc A—B—C so that when used in the rolling operation it will produce a blank of the desired length and contour.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a cam grinding machine having a base, a transversely movable rotatable grinding wheel thereon, a longitudinally movable table on said base, a rock bar on said table, a rotatable master cam spindle on said rock bar, means to rotate said spindle, a work supporting center on said spindle, a footstock having a work supporting center, means including a master cam on said spindle and a follower roller on said table to rock said bar during a grinding operation to generate a predetermined peripheral contour on the work piece, a work driving head rotatably supported on said spindle, means including an adjustable cam mechanism to accelerate the rotation of said driver relative to said spindle, and means to adjust said cam mechanism so as to vary the angular acceleration of the work driver to generate a form of a predetermined peripheral length on the periphery of a work piece being ground regardless of the diameter of the work piece.
2. In a cam grinding machine having a base,

a transversely movable rotatable grinding wheel thereon, a longitudinally movable table on the base, a rock bar on said table, a rotatable master cam spindle on said rock bar, means to rotate said spindle, a work supporting center on said spindle, a footstock having a work supporting center, means including a master cam on said spindle and a follower roller on said table to rock said bar during a grinding operation to generate a predetermined contour on the work piece being ground, a driving flange fixedly mounted on said spindle, a work driver rotatably mounted on said spindle adjacent to said flange, and adjustable driving connections including an adjustable cam mechanism interposed between the flange and driver to accelerate the driver relative to the master cam spindle so that single master cam serves to generate a form of a predetermined peripheral length regardless of the diameter of the work piece.

3. In a cam grinding machine having a base, a transversely movable rotatable grinding wheel thereon, a longitudinally movable table on the base, a rock bar on said table, a rotatable master cam spindle on said rock bar, means to rotate said spindle, a work supporting center on said spindle, a footstock having a work supporting center, means including a master cam on said spindle and a follower roller on said table to rock said bar during a grinding operation to generate a predetermined contour on the work piece being ground, a driving flange fixedly mounted on said spindle, a work driver rotatably mounted on said spindle adjacent to said flange, a radially movable slide on said flange, a non-radial groove on said driver, a roller on said slide which rides in said groove, and means including an adjustable cam mechanism to move said slide so as to accelerate the rotation of the driver relative to said flange to facilitate grinding a form of a predetermined peripheral length on the periphery of the work piece being ground regardless of the diameter of the work.

4. In a cam grinding machine as claimed in claim 3, wherein the work driver further includes a cam fixedly mounted on said rock bar, an adjustable bracket mounted on the periphery of said flange, an arcuate shaped arm having one end pivotally mounted on said bracket, a roller on the other end of said arm engageable with said cam, an elongated arcuate slot in said arm, and a stud on said slide which rides in said slot, the adjustment of said bracket serving to vary the extent of movement of said slide and thereby vary the extent of the accelerated movement of the driver relative to the spindle to facilitate grinding a form of a predetermined peripheral length on the periphery of the work piece being ground.

5. In a cam grinding machine as claimed in claim 3, in combination with the parts and features therein specified of an adjustable stop screw on said flange engageable with a stop surface on said driver, and a tension spring connected between the flange and the driver normally to maintain said stop surface in engagement with the stop screw, said stop screw serving to limit

the position of said arcuate arm and roller thereby to determine the arcuate acceleration of the driver to facilitate grinding a form of a predetermined peripheral length.

6. In a cam grinding machine having a base, a transversely movable rotatable grinding wheel thereon, a longitudinally movable table, a rock bar on said table, a rotatable work support on said rock bar including a rotatable master cam spindle having a work supporting center and a footstock center, means to rotate said master cam spindle, means including a master cam on said spindle and a follower roller on said table to rock said bar during a grinding operation to generate a predetermined contour on the roll to be ground, said master cam being shaped to generate a form of a predetermined peripheral length on a full-size roll to be ground, a work driving head rotatably supported on said spindle, means including an adjustable cam mechanism to accelerate the rotation of the driver relative to the rotation of the spindle, and means to adjust said cam mechanism so as to vary the acceleration of the driver relative to the rotation of the spindle to facilitate grinding a form of the same peripheral length on the periphery of the roll as it is reduced in diameter by successive grinding operations.

7. In a cam grinding machine as claimed in claim 6, in combination with the parts and features therein specified of a work drive block adjustably mounted on said work driving head, and means to adjust said block relative to said head to facilitate positioning of the roll to be ground relative to the master cam.

8. In a cam grinding machine as claimed in claim 3, wherein the work driver further includes a cam fixedly mounted on said rock bar, an adjustable bracket mounted on the periphery of said flange, an arcuate shaped arm having one end pivotally mounted on said bracket, a roller on the other end of said arm engageable with said cam, an elongated arcuate slot in said arm, and a stud on said slide which rides in said slot, the adjustment of said bracket serving to vary the extent of movement of said slide and thereby vary the extent of the accelerated movement of the driver relative to the spindle to facilitate grinding a form of a predetermined peripheral length on the periphery of the work piece being ground, said cam on the rock bar being so shaped that after a predetermined acceleration of the work driver the cam serves to decelerate the movement of the work driver to its initial position during the remainder of each rotation of the work driving head.
